US00D895817S

(12) United States Design Patent (10) Patent No.: US D895,817 S
(45) Date of Patent:  Sep. 8, 2020

(54) PACIFIER FOR BABIES

(71) Applicant: MAPA GmbH, Zeven (DE)

(72) Inventor: Bodo Warden, Viersen (DE)

(73) Assignee: MAPA GmbH, Zeven (DE)

() Term: 15 Years

(21) Appl. No.: 29/655,946

(22) Filed: Jul. 9, 2018

(30) Foreign Application Priority Data

Jan. 10, 2018 (EM) 004660249

(51) LOC (12) Cl. 24-04

(52) U.S. Cl.

USPC D24/194
